(57) **CLAIM**

The ornamental design for a removable mattress pad cover, as shown and described.

DESCRIPTION

FIG. 1 is a perspective view of a removable mattress pad cover showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of a portion indicated with numeric 9 in FIG. 1; and,

FIG. 10 is a perspective view thereof in another state.

The broken lines shown in the drawings represent portions of the removable mattress pad cover that form no part of the claimed design. The dash dot dash broken lines shown in FIG. 1 and FIG. 9 are for the purpose of depicting areas of enlargement and form no part of the claimed design.

1 Claim, 10 Drawing Sheets
